UNITED STATES PATENT OFFICE.

GEORGE W. DOVER, OF CRANSTON, RHODE ISLAND.

PIN-JOINT.

SPECIFICATION forming part of Letters Patent No. 717,555, dated January 6, 1903.

Application filed July 15, 1902. Serial No. 115,637. (No model.)

To all whom it may concern:

Be it known that I, GEORGE W. DOVER, a citizen of the United States, residing at Cranston, in the county of Providence and State of Rhode Island, have invented certain new and useful Improvements in Pin-Joints, of which the following is a specification.

My invention relates to that class of pin-joints commonly known as "open joints" to distinguish them from closed or cup joints, both of which are used in connection with ornamental pins or brooches.

The typical and common form of open joints consists of two upright distended walls or ears rising from a flat base. Traversing each wall and in axial alinement are cylindrical passages or openings of uniform diameter throughout. In such a structure it is impossible to utilize a journal of predetermined length which would be both cheaper and could be more speedily inserted than the pivot commonly used, which is inserted from one side and is cut after insertion in each individual case. This difficulty might theoretically be overcome by making a special bearing-pin with tapering and pointed terminals; but after compression of the walls of the joint it is found by trial that the bearing-pin usually works loosely, which of course gives such an old effect to the brooch that it is not marketable. In any event the projecting points of the bearing-pin cannot be upset as could an obtuse head.

The difficulties above enumerated are obviated by my structure, which is detailed herein conjointly with the accompanying drawings, wherein—

Figure 1 is a side elevation of a brooch or pin upon which is attached my joint, also displayed in similar elevation. Fig. 2 is a transverse section of the above brooch on line xx of Fig. 1, showing the joint-walls distended; and Fig. 3, a similar section of the same, showing the walls in final position engaging the journal-pin of the pin-tongue, the journal and tongue shown in elevation.

Like letters of reference indicate like parts throughout the views.

My new joint is shown affixed to the back 50 of a brooch A. It consists in detail of a base a

and upwardly-directed walls b on either side. The walls originally lie in diverging planes, as shown in Fig. 2. Both walls are transversely pierced at the same relative point in such a manner that the openings c have the 55 shape of truncated cones, the larger diameters being upon the inner faces of the walls. The loop y of the pin-tongue d carries a cylindrical pivot e , which should be sufficiently long to project slightly beyond the outer surface of 60 the walls when the latter are bent into final position. The tongue, with its pivot e , is introduced between the walls b of the joint, with the pivot e in alinement with the openings c . Then with pliers or otherwise the walls b are 65 forced toward each other to a position at right angles to the base a , which results, as above suggested, in the extremities of the pivot e slightly projecting. These are then upset, forming almost imperceptible flanges f g . 70

Having thus described my invention, what I claim as new, and desire to secure by Letters Patent, is—

1. A pin-joint consisting of a base, diverging walls integral with the base and provided 75 with bearing-passages having a larger internal than external diameter.

2. A pin-joint consisting of a base diverging walls integral with the base and provided with bearing-passages of the form of truncated cones. 80

3. In an article of the class described, the combination with a pin-tongue of a cylindrical pivot of substantially uniform diameter throughout, and supporting-walls traversed by bearing-passages for the pivot having larger interior than exterior diameters. 85

4. In an article of the class described, the combination with a pin-tongue of a cylindrical pivot of uniform diameter throughout, 90 and supporting-walls traversed by bearing-passages of the form of truncated cones for the admission of the pivot.

In testimony whereof I have affixed my signature in presence of two witnesses.

GEORGE W. DOVER.
